UNITED STATES PATENT OFFICE.

FRANZ MEYER, OF JENA, GERMANY, ASSIGNOR TO THE FIRM OF CARL ZEISS, OF JENA, GERMANY.

IRIS DIAPHRAGM.

1,411,219.

Specification of Letters Patent. Patented Mar. 28, 1922.

Application filed August 8, 1921. Serial No. 490,735.

(GRANTED UNDER THE PROVISIONS OF THE ACT OF MARCH 3, 1921, 41 STAT. L., 1313.)

To all whom it may concern:

Be it known that I, FRANZ MEYER, a citizen of the German Empire, residing at Jena, Germany, have invented a new and useful 5 Iris Diaphragm (for which I have filed an application in Germany January 26, 1918, Patent No. 305,626,) of which the following is a specification.

The flat, adjustable lamellæ of an iris- 10 diaphragm, on the latter being brought into a horizontal position or one approaching the same, are inclined to sag owing to their weight.

With large diaphragms as used, f. i., for 15 search-lights or for large astronomical telescopes, this property may lead to rendering the opening and closing of the diaphragm difficult or entirely impossible because the construction of the said iris-diaphragms does 20 not admit of strengthening along with the enlargement of the diaphragm in conformity to its diameter the lamellæ accordingly.

According to the invention the above mentioned drawback may, however, be obviated 25 by joining each of the lamellæ to a supporting arm, rotatably disposed about a journal which is connected to the collar carrying the journals of the lamellæ in such a manner that its axis coincides with that of the journal 30 of the lamella united with the respective supporting arm.

The drawing shows a constructional example of a diaphragm corresponding to the invention, viz. in Fig. 1 in a section drawn 35 along the line 1—1 in Fig. 2, whilst Figs. 2 and 3 show a plan elevation each. In Fig. 2 the lamellæ are drawn in the position corresponding to the smallest and in Fig. 3 in that corresponding to the largest aperture of 40 the diaphragm.

The lamellæ marked *a* of which, in order to attain a clear representation, only three are shown in the drawing and which, for the same purpose, proportional to their

length are drawn considerably broader than 45 they are generally carried out, are supported by two collars *b* and *c*, disposed in a casing *d*. The first of the said two collars, *b*, is made of one piece with the casing, i. e. rigidly connected to the same whilst the second, 50 *c*, is rotatably disposed in this casing. Each of the lamellæ is fixed to the collar *b* by means of a pivot *e*, which is firmly riveted to the lamella but rotatable in the collar. The collar *c*, by the rotation of which the 55 diaphragm is to be opened and closed, is provided with radial slits *f*, each of which serves as a guide of a bolt *g*, riveted to one of the lamellæ. In addition, on the casing *d* an annular body *h* is rigidly disposed to 60 which a number of cylindrical pivots *i* equal to the number of the lamellæ is fixed in such a manner that the axes of these pivots coincide with those of the journals *e*. Besides, about the pivots *i* arms *k* are rotatably disposed, each of these being fixed at its free end to that lamella, the axis of rotation of which coincides with its own. As it is obvious, a strengthening of the lamellæ, counteracting to the sagging, is effected by means 65 of the supporting arms *k*, without impairing thereby the freedom of motion of the said lamellæ.

I claim:

In an iris-diaphragm a set of lamellæ, each 75 of which is rotatably disposed on a collar and coacts with a second collar, the two collars being rotatable relatively to each other, and a set of supporting arms, each of which is connected at one of its ends to one of the 80 said lamellæ and rotatably disposed on its other end about an axis coinciding with the axis of rotation of the lamella connected to it.

FRANZ MEYER.
